UNITED STATES PATENT OFFICE

DONALD S. BARROWS, OF ROCHESTER, NEW YORK, ASSIGNOR TO THE GOULD COUPLER COMPANY, OF NEW YORK, N. Y., A CORPORATION OF MARYLAND

SIDE FRAME

Application filed April 26, 1928. Serial No. 273,068.

This invention relates to side frames for railway rolling stock and more particularly to such frames with integral journal boxes. A principal object of my invention, generally considered, is to increase the strength of connection between the ends of the frame and the associated integral journal boxes by spacing the sides of the compression and tension members over said boxes to approximately 10 correspond with the width of the brass lugs.

Another object of my invention is the provision of a truck side frame in which the compression member is formed with a web and depending flanges on either side thereof, 15 said flanges being integrally united with the roofs of journal boxes at the ends thereof, the strength of connection with said boxes being increased by converging the flanges to approximately the width of the brass lugs.

20 A further object of my invention is to provide a truck side frame in which the compression member is generally inverted U-shape in cross section between integral journal boxes at the ends thereof, the strength of 25 the union with said journal boxes being increased by changing said member over the boxes to double I section.

A still further object of my invention is to 30 provide a truck side frame formed with a compression member and a tension member united with journal boxes at the ends thereof, the compression member being formed with an upper web and side flanges depending therefrom and the strength of connection 35 with the boxes being increased by converging the flanges beneath the web to form pockets over the roofs of the journal boxes.

Other objects and advantages of the invention relating to the particular arrangement 40 and construction of the various parts will become apparent as the description proceeds.

Referring to the drawings illustrating my invention, the scope whereof is defined by the appended claims,—

Figure 1 is a plan of one end of a side frame embodying my invention.

Figure 2 is a partial end elevation of said frame.

Figure 3 is a sectional view of the com-

pression member of said frame on the line 3—3 of Fig. 2.

Figure 4 is a sectional view of the tension member of said frame on the line 4—4 of Fig. 2.

Figures 5 and 6 are views corresponding, respectively, to Figs. 1 and 2 but showing a modification.

Figures 7 and 8 are views corresponding, respectively, to Figs. 1 and 2 but showing another modification.

Referring to the drawings in detail, like parts being designated by like reference characters, and first considering the embodiment of my invention illustrated in Figs. 1 to 4, inclusive, there is shown one end of a truck side frame 1, comprising a compression member 2, a tension member 3, and a journal box 4 integrally connected to said frame adjacent the union of the compression and tension members. The intermediate portion of said frame may be of conventional construction and involve bolster guide columns or strut portions, not shown, spacing the intermediate portions of said compression and tension members and spaced apart to leave a bolster opening of conventional or desired character.

The compression member 2, as illustrated particularly in Fig. 3, in the present embodiment is generally inverted U-shape in cross section and formed with an upper web 5 and flanges 6 depending therefrom. The tension member, although shown U-shape in cross section with a lower web 7 and upstanding flanges 8, may be of other configuration if desired. The web 7 of said tension member is connected to the inner side wall of the journal box adjacent the roof thereof by being extended to the junction between said roof and side wall and preferably reinforced by triangular gusset portions 9. The strength of connection between the tension member and inner side wall of the box may be further reinforced by a tie or strut portion 10 which is preferably angular in section. Although only one end of the frame is illustrated, it will be understood that said frame is symmetrical and the other end corresponds with the end shown.

The journal box, as is usual, is provided with inner and outer brass lugs 11 and 12, respectively. Said brass lugs, although not primarily for that purpose, act as reinforcements in the side walls of the box. For greatest strength of connection between the box and the compression and tension members it is therefore important that said members unite with the roof of the box as near as possible to the reinforcing brass lugs. In order, however, to get sufficient strength in the compression and tension members the same are preferably generally considerably wider than the width of said brass lugs. In order, therefore, to increase the strength of connection between the frame members and the roof of the box I preferably gradually converge the sides 6 of the compression member which are also continuations of the sides 8 of the tension member adjacent the box inwardly beneath the web 5 of the compression member so that over the roof of the journal box their distance approximately corresponds with the width of the brass lugs 11 and 12. In the particular embodiment the flanges 6 converge together to approximately the width of the brass lugs adjacent the vertical center line of the box and from there extend onward parallel to each other and are discontinued at the outer side wall of the box by merging with the web 5 which preferably curves downwardly to aline and merge with the outer side wall 13 of said box 4. In order to effect a saving in weight of material the web 5 between the flanges 6 of the compression member is preferably discontinued short of a union with the roof of the box. This discontinuance also facilitates core removal. It will be evident that this construction provides for a substantially direct union between the flanges 6 of the compression member and those portions of the roof of the box at or adjacent the brass lugs 11 and 12 so that a very secure connection between the frame members and the box is effected.

Referring now to the embodiment of my invention illustrated in Figs. 5 and 6, a construction is there disclosed in which the side frame 1^a is, as before, formed with a compression member 2^a, a tension member 3^a, and an integral journal box 4^a. Said compression member comprises an upper web 5^a and side flanges 6^a, as in the first embodiment. The side flanges, however, do not converge gradually from a considerable distance inwardly of the journal box 4^a but start to converge approximately directly over the inner wall 14 of the journal box 4^a and curve toward each other so that they merge together approximately directly on the vertical center line of the journal box as indicated at 15. From there to the outer brass lug 12^a of the box they extend as a single flange or web 16 where they merge with the web 5^a of the

compression member which is curved downwardly to aline and merge with the inner wall of the brass lug 12^a.

The foregoing construction, as will be apparent, results in a rigidification of the roof of the journal box in the region of the brass lugs so that the compression member, and of course the tension member which merges therewith at the ends of said members, are thereby very securely connected to the journal box. On account of the converging of the flanges of the tension and compression members beneath the web of the compression member and above the roof of the box, pockets 17 are formed between said box and the web 5^a of the compression member as in the previous form. Except as specifically described in connection with the present embodiment the same may correspond with that of the first.

Referring now to the embodiment of my invention illustrated in Figs. 7 and 8, a side frame 1^b is there disclosed having a compression member 2^b, a tension member 3^b, and a journal box 4^b integral therewith. Both compression and tension members may have webs 5^b and 7^b, respectively, with flanges 6^b and 8^b, respectively, extending toward each other and merging at the junction between the members where they unite with the journal box.

In order to rigidify the connection with the journal box the side flanges 6^b and 8^b of the members are caused to converge toward each other beneath the web 5^b of the compression member preferably directly over the inner brass lug 11^b so that said side walls are concave outwardly and are spaced closest together immediately over the inner brass lug 11^b and approximately the same distance apart as the width of said brass lug so that they merge with the roof of the journal box 4^b at approximately the same place that the brass lug connects therewith. This construction results in pockets 17^b as in the previous embodiment except that said pockets are spaced near the inner brass lug rather than near the outer brass lug. Beyond the pockets 17^b the flanges 16 are continued at the normal distance apart to the outer side wall 13^b of the journal box and merge with the roof thereof on either side of the outer brass lug 12^b. As in the first form of my invention the web 5^b of the compression member 2^b is discontinued short of a union with the roof of the journal box between the flanges 6^b thereof. Except as specifically disclosed in connection with the present form of my invention, the same may correspond with that of the first embodiment.

In the foregoing description I have shown how the connection between the integral journal boxes and the ends of a side frame having tension and compression members, respectively **U** and inverted **U** in cross section, may be rigidified. It will be obvious, how-

ever, that I do not wish to be limited to a construction in which the side frames are so shaped, as certain of the advantages of my invention may be secured in connection with side frames having members shaped other than as disclosed in the present application.

Having thus described my invention, what I claim is:—

1. A truck side frame comprising a compression member and a tension member uniting at their ends, journal boxes integrally united to the frame at the ends of said members, the union with said journal boxes being strengthened by causing the sides of the members to converge over the roofs of the boxes to a width less than that of the top wall of the compression member.

2. A truck side frame comprising a compression member and a tension member united together and a journal box adjacent the end of the frame, the union of said members with said box being strengthened by causing the sides of said members to converge, beneath the top wall of the compression member to a width less than said wall, to approximately the width of the brass lugs and unite with the roof of the box.

3. A truck side frame comprising U-shaped compression and tension members uniting at their ends, journal boxes integrally united to the frame adjacent the ends of said members, said members changing from U to double I section over the journal boxes for increasing the strength of connection therewith.

35 4. A truck side frame comprising a compression member, a tension member, said compression member being generally inverted U-shape in cross section and the tension member being generally U-shape in cross section, the side flanges of said members uniting together, and a journal box integral with said members at the ends thereof, the strength of connection with said journal box being increased by converging the side flanges of the members beneath the web of the compression member to form pockets over the roof of the journal box.

50 5. A truck side frame comprising a compression member generally inverted U-shape in cross section, and a journal box integrally connected beneath the end thereof to the sides of said member, the strength of connection therewith being increased by spacing the side flanges of said member over the roof of the journal box to approximately correspond with the width of the brass lugs.

60 6. A truck side frame comprising a compression member and a tension member uniting at their ends, journal boxes integrally united to the frame at the ends of said members, the union with said journal boxes being strengthened by converging the sides of the members over the roofs of the boxes and extending the compression member to unite directly with the outer brass lug.

7. A truck side frame comprising a compression member generally inverted U-shape in cross section with a web and depending flanges, a journal box united to said flanges, the strength of connection being increased by converging said flanges over the inner brass lug of said box to approximately the width thereof.

75 8. A truck side frame comprising a compression member generally inverted U-shape in cross section with a web and depending flanges, a journal box integral with said flanges at the end of said member, said flanges converging together over the roof of said box, and the web continued to unite with the inner wall of the outer brass lug.

80 9. A truck side frame comprising a compression member generally inverted U-shape in cross section with a web and depending side flanges, and a journal box integral therewith, said flanges uniting with the roof of the box and converging together at approximately the vertical center line of said box.

85 10. A truck side frame comprising a compression member generally inverted U-shape in cross section with a web and depending flanges, a journal box integrally united to said flanges, said flanges over the inner brass lug of said box being curved inwardly beneath the web of said member to approximately the width of said lug.

90 11. A truck side frame comprising a compression member with an upper web and flanges depending from the sides thereof, a journal box integral with the lower portion of said flanges, the connection with said journal box being strengthened by causing said flanges to gradually converge toward each other beneath the web of the member from a point inwardly of the journal box until they are approximately the same distance apart as the width of the brass lugs.

In testimony whereof I affix my signature.
DONALD S. BARROWS.
